UNITED STATES PATENT OFFICE.

VIRGIL D. PORTER, OF BIRMINGHAM, ALABAMA, ASSIGNOR OF ONE-HALF TO WILLIS A. MASSEY AND ORLAND F. PARKS, BOTH OF BIRMINGHAM, ALABAMA.

AUTOMATIC OPERATING MECHANISM FOR RAILWAY GATES.

Application filed February 11, 1924. Serial No. 691,951.

To all whom it may concern:

Be it known that I, VIRGIL D. PORTER, a citizen of the United States of America, residing at Birmingham, in the county of 5 Jefferson and State of Alabama, have invented certain new and useful Improvements in Automatic Operating Mechanism for Railway Gates, of which the following is a specification.

10 My invention relates to an automatic operating mechanism for opening and closing railway crossing gates. My invention belongs to that class of operating mechanisms in which the train as it 15 approaches and as it departs from the crossing will by mechanical or electrical appliances directly or indirectly cause the automatic closing of the crossing gates ahead of the train and their opening after 20 the train has passed the crossing.

Heretofore, in such appliances, it has been the general practice to utilize train trip mechanism either to actuate the gates mechanically to open or close them, or to 25 energize an electric motor drive which would positively open or close the gates. Obviously such appliances, being entirely automatic in their action, are subject to certain inherent objections such as that, being positively driven, they may in closing strike a 30 vehicle or they may trap the vehicle between the gates on the tracks and under these conditions either the vehicle is damaged or destroyed or the gate mechanism must be 35 broken to allow its escape. Moreover, these mechanisms are further subject to the objection that they are expensive, require attention and are thus impractical for use except where they can be kept under constant 40 observation.

The purpose of my invention is to devise a gate controlling mechanism which may be mechanically or electrically operated under control of the train and which is distinguished from electrically or mechanically 45 driven gates by the manner in which the gate is caused to open or close, this being a motion always free and responsive only to gravity, and is preferably accomplished by a very slight shifting of the gate axis. Obviously this arrangement relieves the operating mechanism of any positive connection to the gate to operate it, and of any appreciable 50 load or duty as the shifting of the gate's axis or pivot offers so little resistance that

it is possible to mechanically operate it by a positive drive from a rapidly moving train without probable destruction of the operating mechanism.

The advantages of my invention and its 60 preferred methods of operation will be more clearly understood by reference to the accompanying drawings which form a part of this specification, and in which:—

Fig. 1 is a plan view of a track equipped 65 with a mechanical drive for shifting the lower pintle bearing of the gate.

Fig. 2 is a side elevation of Fig. 1; and

Fig. 3 an enlarged plan view of a gate showing its stops and the bearing for the 70 lower pintle in position to cause the gate to close.

Fig. 4 is a plan view of a double crossing gate electrically controlled.

Fig. 5 is an enlarged end elevation of a 75 gate shown in closing position.

Fig. 6 is a detail plan view of the guide bracket for the movable pintle bearing.

Fig. 7 is an enlarged sectional view of the 80 pintle and its bearing and guide.

Similar reference numerals refer to similar parts throughout the drawings.

According to the embodiment of my invention illustrated in Figs. 1 to 3 I show a railway track comprising rails 1, cross ties 2, and dotted lines 3 indicating a roadway crossing the track. The gate mechanism shown is of the simplest possible type comprising a single horizontally swinging gate 4 on each side of the crossing, but obviously 85 the type of gate may be varied at will. Adjacent to the railway on opposite sides of the road I place two upright posts 5 and I attach to the top of these posts a metal strap or bracket 6 which overhangs and has 90 an opening to receive the top pintle 7 of its respective gate 4. Near the bottom of each post I attach a bracket 8 having therein a diagonal slot 9. A transversely disposed operating bar 10 for each gate has at its 100 outer end a hole 11 in which is received the lower pintle 12 of the gate, which projects below the bar and carries a roller 12^a which works in and is guided by the slot 9. Each bar 10 at its inner end is received in guides 105 13 suitably attached to the cross ties and has an upturned pin 14 which is engaged in an angled slot 15 of its respective throw plate 16 which is connected to or rigid with an operating rod or shaft 17 that extends cen- 110

trally between the track rails to a suitable distance on each side of the roadway sufficient to allow ample time for the closing of the gate when the shaft is actuated by the train.

The shaft has suitable guides 18 and at one end is provided with a downwardly offset rack 19 having upturned teeth and at the other end with a straight rack 20 having downturned teeth. The racks 19 and 20 are respectively engaged by gears 21 and 22, the former being above the rack 19 and the latter below the rack 20. Each of the gears is fast on a rocker shaft 23 having upturned end fingers or arms 24 which are adapted to be engaged by any suitable element on an approaching train and rocked to shift the shaft longitudinally of the track. The rocker shafts 23 are journaled in suitable bearings 25 clipped to the rails or otherwise secured to the track. The shaft is provided with a throw plate 16 for each gate operating bar 10 and the slots 15 are reversely arranged in these plates so as to cause both gates to open or close in unison according to the direction of movement of the bar imparted thereto by the train trip which is typically illustrated at 26 in Fig. 2. Each gate is also provided with brackets 27 having stop arms on each side of the gate so as to limit its inward and outward play. The bars 10 will stand either in their extreme inner or extreme outer positions, it not being possible for them to be left in an intermediate position and when in either extreme position the lower pintle of the gate is shifted out of vertical alignment with the upper pivot so as to unbalance the gate and cause it by gravity to open or close according to the direction in which the gate is unbalanced, (see Fig. 5). It will be observed, however, that it is merely the pintle of the gate which is displaced by the operating mechanism, the gate itself being at all times free to swing and thus as it moves to close it will move gently and slowly and without possible injury or damage to any passing animal or vehicle, and moreover should the gates by any chance enclose between them a vehicle, obviously they can be opened with entire freedom so that the vehicle can pass on out of the track. Further, being light and free of any rigid operating mechanism, the gates can be opened outwardly from the track by driving into them and which would open them without injury to an automobile or vehicle. The shaft 17 and the throw plates 16 are made very light so that the inertia will be negligible and if desired antifriction bearings 18 may be used for the shaft. The wedging action of the throw plate slots on the operating bars 10 presents negligible resistance to the free longitudinal movement of the bar as the throw plates have practically no duty due to the fact that

they shift only the lower gate axis while the weight of the gate is supported overhead by the bracket 6 preferably by the use of an antifriction bearing 39. My invention contemplates that the thrust of the gate on the lower pintle 12 shall be taken by the roller 12^a.

In operation, an approaching train moving to the right, Fig. 2, will by means of its trip 26 throw the arms 24 of the near rocker shaft 23 clockwise and draw the operating shaft 17 to the left. This moves the two throw plates to the left and shifts their slots so as to force the bars 10 outwardly, thus throwing the bottom pintles of the gate outwardly and unbalancing the gates to cause them to swing closed. At the same time the arms 24 on the far rocker shaft 23 will be swung counter-clockwise and when the trip actuates them they are drawn clockwise by the train and the shaft 17 is thrown to the right, causing the gate pintles to be drawn inwardly and the gates unbalanced to swing open. The same action occurs when the train approaches in the opposite direction.

In Fig. 4 I show a gate mechanism adapted for electrical operation. Here the track rails throughout the desired zone on each side of the crossing are insulated and connected by an electrical circuit 28 to a source of electrical energy such as a battery 29 and included in the circuit 28 is a solenoid or electric-magnet 30 for each gate, the core or armature 31 of which solenoid is connected by a lever 32 to a bar 33 corresponding to the bar 10 and serving to guide the lower gate pintle 12 in the diagonal slot 9 of the bottom bracket 8^a corresponding to 8. The lever is pivoted to the bracket 8^a. A coil spring 34, connected to a suitable anchor and to said lever tends normally to shift the bar 33 inwardly so as to unbalance the gate to cause it to swing open. In this arrangement I have shown a pair of gates 35 on one side of the track. This arrangement being more suitable for wide crossings. It may be desirable to put a positive stop 36 in the center of the roadway which will stop the closing movement of the gates and prevent them being opened inwardly to give access to the track, but these stops obviously do not interfere with the opening outwardly of the gates from the track.

It will be understood that both the mechanical and electrical appliances described for the unbalancing of the gates are capable of wide variation without departure from the essential spirit of my invention. The operation of the electrical appliances is identical with that of the mechanical appliances. As soon as a train passes onto the insulated track section and so long as it remains thereon the magnets are energized and the gates unbalanced to close. The moment the in-

sulated track is clear of the train, the circuit to the magnets is broken and the springs shift the pintles 12 to unbalance the gates so that they will swing open and remain in this 5 position until another train passes onto the insulated track section. The source of electrical energy is typically indicated as a battery but it may be a generator on the railroad train itself or a battery carried by 10 the train or it may be connected up with any suitable source of electricity, either local or such as may be available along the track for other signal purposes.

If desired a warning lamp 37 may be 15 mounted on the gates and connected by a circuit 38 across the magnet circuit so as to be illuminated when and while the magnets are energized.

Though I have described with great particularity the details of the embodiment of the invention herein shown, it is not to be construed that I am limited thereto, as changes in arrangement and substitution of equivalents may be made by those skilled in the art 25 without departing from the invention as defined in the appended claims.

Having thus described my invention, what I claim as new and desire to secure by Letters Patent, is:—

30 1. In a railway crossing gate mechanism, gates having substantially vertical axes, train controlled mechanism adapted to shift said axes out of vertical position on each

side to unbalance the gates, said mechanism comprising an electric track circuit adapted 35 to be closed by an approaching train, a magnet for each gate energized by the closing of said circuit, a shifter bar operable by each magnet and connected to the lower vertical axis of its respective gate, and a bottom bearing plate for each lower gate axis having a diagonal guide slot for each axis, and spring means to reset the shifter bar when the magnet is de-energized, and means to stop the opening and closing movements of the gates, 45 said gates being at all times free to swing on their respective axes between their respective stop means.

2. In a railway crossing gate mechanism, a support carrying upper and lower bearings 50 for the gate, upper and lower pintles of the gate working in said bearings, means to support the weight of the gate from the upper pindle, there being a diagonally arranged slot in the lower bearing to receive the lower 55 pindle, a roller on the lower pindle to take the thrust of the gate, a shifting plate mounted on the lower pindle, and train controlled mechanism to shift said lower pindle laterally to unbalance the gate, as and for 60 the purposes described.

In testimony whereof I affix my signature.

VIRGIL D. PORTER.
